ATTORNEY.

UNITED STATES PATENT OFFICE.

CHARLES D. FOSTER, OF PHILADELPHIA, PENNSYLVANIA.

UMBRELLA FOR CHILDREN'S CARRIAGES.

SPECIFICATION forming part of Letters Patent No. 288,703, dated November 20, 1883.

Application filed July 14, 1883. (No model.)

To all whom it may concern:

Be it known that I, CHARLES D. FOSTER, a citizen of the United States, residing in the city and county of Philadelphia, State of Pennsylvania, have invented a new and useful Improvement in Umbrellas or Parasols for Children's Carriages, which improvement is fully set forth in the following specification and accompanying drawings, in which—

10 Figure 1 is an elevation, partly in vertical section, of an umbrella or parasol embodying my invention. Fig. 2 is a vertical section of a portion of Fig. 1 enlarged, the umbrella being open. Fig. 3 is a view of the same closed.

15 Similar letters of reference indicate corresponding parts in the several figures.

My invention consists of an umbrella or parasol for a child's carriage, formed with means, substantially as hereinafter described, 20 whereby it may be easily attached to the supporting-arm, is firmly connected therewith, and may be readily removed therefrom.

It also consists of the construction of an umbrella or parasol with a short stick, and a 25 runner which is constantly engaged with the stick, so that the difficulty of guiding the runner on said short stick in opening the umbrella or parasol is avoided.

Referring to the drawings, A represents the 30 frame of an umbrella, of which B are the ribs, C the stretchers, and D the runner.

E represents the stick, which is a short piece, and terminates just below the fastening-catch of the runner, or adjacent to the lower ends 35 of the stretchers when the same are open, so that it is prevented from striking the occupant of the carriage.

Heretofore the construction of the runner has been such that when the umbrella is closed 40 said runner leaves the stick, so that when the umbrella is to be opened considerable difficulty is experienced in refitting the runner on the stick. This is obviated by my construction of the runner, the same consisting in extending 45 or elongating the runner at its upper end, so that it remains constantly on the stick, especially when closed, (see Fig. 3,) whereby it requires no manipulation to cause the short stick to enter the same. Furthermore, short 50 stretchers are employed, thus strengthening the same and reducing the expense thereof,

said stretchers being pivoted to the bottom of the runner, which limits the length of the runner.

To the portion of the stick or ferrule above 55 the frame A is secured a spring-catch, F, for holding a removable sleeve, G, by means of which the supporting-arm H of the umbrella is connected with the stick, and the umbrella thereby sustained. The eye or boss of the 60 arm H and the stick are fitted together, and the sleeve G is placed on the stick over said arm and engaged by the catch F, whereby the sleeve and arm are held connected with the stick, and the umbrella is thereby firmly and 65 securely sustained in position, it being seen that the umbrella is permitted to roll with much freedom on the eye or boss of the arm, thus maintaining the proper position on the carriage regardless of the irregular motions of 70 the latter. By forcing in the spring-catch the sleeve may be removed and the umbrella and arm disconnected, it being seen that the operations of connecting and disconnecting the umbrella and arm may be accomplished with 75 ease and rapidity. The sleeve provides a uniform support or means of dependence of the umbrella from the arm, and may be of the form of a hollow sphere, cone, or cylinder.

When the spherical form of the sleeve is 80 employed, the catch may be concealed therein, as shown in Fig. 3, and the rounded form of the same readily causes the catch to be overcome when power is applied to said sleeve.

When the conical or cylindrical form of the 85 sleeve is employed, the bottom of the same may be flaring to permit the rolling of the umbrella thereon, the catch entering a slot in the sleeve or engaging with the top edge thereof, as desired, or entering a swell or bulge in the sleeve, 90 so as to be concealed, similar to that occasioned by the use of the sleeve of spherical form.

Having thus described my invention, what I claim as new, and desire to secure by Letters Patent, is—

1. An umbrella or parasol stick having in its top or ferrule part a fastening-catch, in combination with a sleeve removably fitted to the stick below said catch, and a supporting-arm, said sleeve resting freely on the eye of said arm and rolling thereon, substantially as and for the purpose set forth. 95

2. An umbrella or parasol formed with a short stick terminating near the lower end of the stretcher when open, and a runner which is elongated in an upward direction, whereby it remains on the stick when the umbrella or parasol is closed, substantially as and for the purpose set forth.
3. An umbrella or parasol formed with a stick terminating adjacent to the lower ends of

the stretchers when the same are open, and to an upwardly-elongated runner having short stretchers pivoted to its lower end, substantially as and for the purpose set forth.

CHAS. D. FOSTER.
